UNITED STATES PATENT OFFICE.

HERMAN THOMASS, OF BROOKLYN, NEW YORK.

DESIGN FOR A ROCKING FRAME FOR BELL TOYS.

SPECIFICATION forming part of Design No. 25,579, dated June 2, 1896.

Application filed February 13, 1896. Serial No. 579,186. Term of patent 7 years.

To all whom it may concern:

Be it known that I, HERMAN THOMASS, a citizen of the United States, residing in Brooklyn, in the county of Kings and State of New York, have invented a new Design for Rocking Frames for Bell Toys, of which the following is a specification.

The leading feature of my design consists of a pair of rockers and a platform, the center of which forms a depression, under which the bell is displayed.

In the accompanying drawing the design is represented by a perspective view.

The frame consists of a pair of curved rockers A A and a platform B, the center of which forms a U-shaped depression C, below which the bell D is displayed. The presence of the bell is emphasized by this depression and is

shown to better advantage than if it were situated under a flat part of the platform. 20 The depression and the curved rockers, being nearly concentric, harmonize well together. The central depression, furthermore, divides or breaks the otherwise long stretch of the platform into two shorter sections and 25 thereby gives the frame a symmetric appearance.

Having fully described my design, what I claim as new, and desire to secure by Letters Patent, is—

The design for a rocking frame for bell toys herein shown and described.

HERMAN THOMASS.
